UNITED STATES PATENT OFFICE.

BRAINERD DYER, OF HUDSON, OHIO.

DESIGN FOR A TABLE OR ARTICLE OF SIMILAR NATURE.

Application filed March 23, 1927. Serial No. 21,277. Term of patent 3½ years.

To all whom it may concern:

Be it known that I, BRAINERD DYER, a citizen of the United States, residing at Hudson, in the county of Summit and State of Ohio, have invented a new, original, and ornamental Design for a Table or Article of Similar Nature, of which the following is a specification, reference being had to the accompanying drawing, forming a part thereof.

In the drawing:

Fig. 1 is a top plan view of a table, or article of similar nature showing my new design; and

Fig. 2 is a side elevation of a table, or article of similar nature showing my new design. It is to be understood that a portion only of the ornamentation is shown in the drawing and that the remainder of the ornamentation is identical with that shown.

I claim:

The ornamental design for a table, or article of similar nature substantially as shown and described.

In testimony whereof I affix my signature.

BRAINERD DYER.
